UNITED STATES PATENT OFFICE.

KASSON FRAZER, OF SYRACUSE, NEW YORK.

IMPROVEMENT IN BUCKLES, RINGS, &c.

Specification forming part of Letters Patent No. 35,150, dated May 6, 1862.

To all whom it may concern:

Be it known that I, KASSON FRAZER, of Syracuse, county of Onondaga, and State of New York, have invented a new and useful Improvement in Buckles and Rings; and I do hereby declare the following to be a full, clear, and exact description of the construction and operation of the same, reference being had to the annexed drawings, making part of this specification.

Figure 1 represents a piece of wire cut of the requisite length to form a buckle-frame. Fig. 2 represents the wire bent in the requisite form for a buckle and ready for the ends to be joined. Fig. 3 represents the buckle-frame with the ends of the wires joined firmly together. Fig. 4 represents a ring formed of a piece of wire and its ends joined firmly in the same manner as those of the buckle-frame.

Heretofore the common method of constructing buckle-frames and rings has been by bending the wire in the necessary form and simply bringing the ends in contact, or, in the latter, of welding the ends together.

The nature of my invention consists in connecting the ends of wire or other metallic pieces used in the construction of buckle-frames and rings by means of a sort of dovetail or ball-and-socket connection, as herein-after more fully described.

In constructing my invention the wire from which the frame A and the ring D are to be formed is cut in pieces of the requisite length by means of a die so shaped as to form the head B on one part of the cut wire and the socket or recess C on the other part of the wire

for the reception of the head B. The wire is then bent by proper machinery in the form necessary to construct a buckle-frame or ring and the ends are brought opposite each other. The ends are then forced laterally together, the head B entering the recess C. The whole is then placed under a drop-press, and a blow sets the projections E and F into the neck of the head B, giving a smooth surface to the parts at the point of connection and attaching the ends together in a solid manner.

I am aware that the ends of the wire or rod used in forming buckle-frames have heretofore, and under a patent granted some years since, been connected by forming a head upon each end of the wire or rod and bending around them a grooved ring on the end of the buckle-tongue. I do not claim such a method of connection.

By this my invention a most convenient and useful practical method is furnished of connecting the ends of wire rod used in constructing buckle-frames, rings, links, and other articles in which such a connection may be applicable.

What I claim as my invention, and desire to secure by Letters Patent, is—

The method described of connecting the ends of wire rod used in forming buckle-frames and rings—that is, when the two ends are firmly joined together by interlocking, substantially as stated, and for the purpose set forth.

KASSON FRAZER.
